Inventor:

E. M. D. 1900

JOHN CETERS, INC., LITTLETON, MASSACHUSETTS, U.S.A.

UNITED STATES PATENT OFFICE.

JAMES S. ANDREWS, OF NEW YORK, N. Y.

FREIGHT-CAR.

No. 901,413.

Specification of Letters Patent.

Patented Oct. 20, 1908.

Application filed January 24, 1908. Serial No. 412,374.

To all whom it may concern:

Be it known that I, JAMES S. ANDREWS, a citizen of the United States, residing at New York city, in the county of New York and State of New York, have invented new and useful Improvements in Freight-Cars, of which the following is a specification.

This invention relates to improvements in freight cars and its object is to increase the capacity of the car in proportion to its length.

My invention contemplates increasing the capacity of a car of given length or maintaining the capacity and reducing the length of the car. If a car of a given length has its capacity increased the length of a train required to transport a given quantity of freight will be correspondingly shortened, and the same is true if cars are shortened in length while still maintaining their former capacity.

Besides effecting a material saving in the general expense of equipping, maintaining and operating a railroad, in so far as transportation of freight is concerned, the invention has other advantages which will be apparent to railway officials and employees. Among such advantages may be mentioned the fact that a freight train made up with cars embodying my invention requires less room on a siding than if made up with ordinary cars carrying the same quantity of freight. Consequently when a freight train has been run on a siding to permit a through train to pass, there is less likelihood that the rear car of the freight train will be left projecting in the path of the through train. It may also be mentioned that my invention greatly facilitates the loading and unloading of cars.

The invention also has for its object to provide a freight car of strong and substantial construction and large capacity having an underframe composed of standard sections consisting of steel castings securely and rigidly fastened together.

In the accompanying drawings illustrating one embodiment of the invention Figure 1 is a top plan view of the car. Fig. 2 is a bottom plan view of the underframe. Fig. 3 is an enlarged detail elevation of a portion of one side of the car. Fig. 4 is a longitudinal sectional view on the line 4—4 of Fig. 1. Fig. 5 is an end view of the car. Fig. 6 and Fig. 7 are transverse sectional views on the lines 6—6 and 7—7 of Fig. 1.

Referring to the drawings, the side sills consist of two end sections 8 and a central section 9, these sections being all preferably made of cast steel and rigidly secured together at their adjacent ends. At each end of the frame is a draw-bar sill 10 suitably formed to receive the draw-bar and its attachments. The draw-bar sills are provided with side projections 11 to abut against side projections 12 on the side sills and form the body bolsters and also with side projections 13 to abut against side projections 14 on the side sills to form the end sills. Each of the draw-bar sills has a pair of parallel projections 15 of channel form to which the end of the U-shaped center sill 16 is secured. All of the sections of the underframe are preferably made of cast steel and they may be connected together in various ways but in order to provide for the proper strength and to secure the sections together in a firm and rigid manner I prefer to employ wedge shaped tie plates overlapping the joints and fastened to the sections by bolts or other suitable fastening means as set forth in my application Serial No. 394,790 filed September 27, 1907. Thus the side sill sections are secured together by wedge plates 17 (Fig. 3), the end sill projections by wedge plates 18 (Fig. 5), the bolster projections by wedge plates 19 (Fig. 6) and the center sill to the projections 15 by wedge plates 20 (Fig. 4).

The central sections 9 of the side sills are deeper than the end sections and the latter gradually increase in depth at 8' from the bolster to their inner ends to make a flush joint with the ends of the central sections, as clearly shown in Fig. 3. The center sill is depressed at its central part 16' (Fig. 4) and this central part is connected at its ends by upwardly inclined parts 16'' to the draw-bar sills. The lower edge of the center sill and the draw-bar sills lies in substantially the same horizontal plane as the lower edge of the side sills but the upper edge of the central part 16' of the center sill lies below the upper edge of the central sections of the side sills (Fig. 7). Cast steel transoms 21 are supported on the flanges 22 at the bottom of the side sills and on flanges 23 at the bottom of the center sill and the draw-bar sills and these transoms are deeper at their inner ends than at their outer ends and have their upper edges provided with a plurality of steps 24 to support the stringers 25 (Figs. 5-7).

The flooring is horizontal at 26, 26 at the ends of the car where it is supported on the stringers 25 and the flanges 22' at the top of the side sills (Fig. 7). The flooring is inclined from the top of the center sill downwardly and outwardly to the bottom of the side sills at the central part 27 of the car. Between the flooring 27 at the central part of the car and the horizontal flooring 26, 26 at the ends of the car the flooring 28 is also inclined from the center sill to the side sills (Fig. 7). Thus the car is provided with a flooring which is horizontal at the ends of the car and depressed between the ends of the car, the depressed part being high in the longitudinal center of the car (but not so high as the flooring at the ends of the car) and inclined downwardly and outwardly to the bottom of the side sills.

The sides and ends 29 of the car may be made of sheet metal supported by uprights 30 fastened to the side sills. To facilitate the removal of freight from the depressed parts at the center of the car I prefer to provide one or more doors 31 in each side of the car of any suitable construction. In the drawings I have shown two sliding doors in each side of the car connected by chains 32 with ratchet mechanism 33 for lifting them. Any kind of door and any kind of lifting mechanism suitable for the purpose may be employed.

My invention increases the capacity of a car to the extent of the capacity of the depressed bottom thereof and at the same time the novel construction of the underframe in cast steel sections rigidly and securely fastened together provides a strong and substantial car capable of sustaining the weight of the additional freight which may be carried. Furthermore the interior of the car is not obstructed by girders or braces which would interfere with loading and unloading.

It is well known that there are certain fixed limitations on the height and width of cars but my invention enables the increase of the capacity of a car without increasing its height or width and also enables the reduction of the height and width of a car without reducing its capacity.

What I claim and desire to secure by Letters Patent is:

1. A floor for a railway freight car horizontal at the ends of the car, a central part lower than the ends, reversely inclined parts connecting the central part and the ends, the said central part being inclined reversely and downwardly from the center to the sides of the car.
2. A floor for a railway freight car horizontal at the ends of the car, a central part

lower than the ends and inclined reversely and downwardly across the car from the center to the sides of the car, and parts connecting the ends with the central part and inclined reversely and downwardly lengthwise of the car from the ends to the central part and each inclined across the car reversely and downwardly from the center to the sides of the car.

3. In an underframe for railway cars, two side sills each having a central part deeper than its end parts, a center sill depressed between its ends, and a floor supported on the center sill and the side sills and inclined reversely and downwardly from the center sill to the side sills.

4. In an underframe for railway cars, two side sills each having a central part deeper than its end parts, two draw-bar sills lying in a plane with the top of the side sills, a center sill to support the floor and having a depressed central part and upwardly inclined ends to connect with the draw-bar sills, and a floor supported on said sills, said floor being flat at the ends of the car and inclined reversely and downwardly from the center sill to the side sills at the central part of the car.

5. In an underframe for railway cars, two side sills each having a central part deeper than its end parts, two draw-bar sills lying in a plane with the top of the side sills, a center sill to support the floor and having a depressed central part and upwardly inclined ends to connect with the draw-bar sills, and a floor supported on said sills, said floor being flat at the ends of the car and inclined reversely and downwardly from the center sill to the side sills at the central part of the car.

6. In an underframe for a railway car, a cast steel transom higher at its inner end than at its outer end and having an inclined upper edge.

7. In an underframe for a railway car, a cast steel transom having an inclined upper edge with a plurality of steps.

8. A railway freight car comprising a pair of side sills each having a central part deeper than the end parts, a center sill having a depressed central part, a plurality of transoms extending from the central part of the center sill to the deep part of the side sills, said transoms having steps thereon, stringers on said steps, and a flooring on said stringers inclined downwardly from the center of the car to its sides.
